Fig. 1.

Fig. 2.

A circular seal or emblem is shown, featuring a central circular hole and a textured, concentric outer edge. The number '12' is written in the upper right quadrant of the inner circle, and '24' is written in the lower right quadrant. The number '10' is written in the lower right quadrant of the outer circle. The entire emblem is set against a background with a cross-like shape and some curved lines.

UNITED STATES PATENT OFFICE.

ARTHUR YERLY, OF GARY, INDIANA.

ROLLING WINDOW SCREEN.

Application filed March 21, 1919. Serial No. 283,978.

To all whom it may concern:

Be it known that I, ARTHUR YERLY, a citizen of the United States, residing at Gary, in the county of Lake and State of Indiana, ⁵ have invented new and useful Improvements in Rolling Window Screens, of which the following is a specification.

The present invention comprehends generally improvements in that class of inventions known as curtains, shades and screens and more particularly relates to a rolling window screen.

The invention has for its principal aim and object to provide a device of the above ¹⁵ mentioned character designed to be readily connected to the frame of a window and of a construction that is capable of being extended and fastened so as to completely close the window casing or else may be fastened and rolled up to permit of the complete detaching of the device from position when it is not desired to use the same.

More particularly the present invention contemplates the provision of a device of the ²⁵ above mentioned character wherein improved cooperative means is mounted on the window frame and on the edges of the body of the screens for guiding the screens when it is being adjusted and for preventing the ³⁰ screens from sagging when extended.

It is a more specific object of the present invention to provide a device of the above mentioned character wherein improved means is employed for detachably fastening ³⁵ the screens in an extended position; and to also provide clamping means for reinforcing the guides.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be exemplified in the construction hereinafter described and the scope of the ⁵⁰ application of which will be indicated in the appended claim.

The invention is clearly illustrated in the accompanying drawings, in which:

Figure 1 is a front elevation of the device. ⁵⁵
Figure 2 is a vertical longitudinal sectional detail.

Figure 3 is a vertical transverse section of the device applied.

Figure 4 is a transverse horizontal section on line 4—4 of Figure 1. ⁶⁰

Figure 5 is a transverse horizontal section on line 5—5 of Figure 1.

Figure 6 is an enlarged transverse sectional detail on line 6—6 of Figure 1.

Figure 7 is a perspective detail of a portion of the screen, and ⁶⁵

Figure 8 is a detail of the clamp.

Similar characters of reference are employed in all of the above described views, to indicate corresponding parts. ⁷⁰

Referring now, more particularly, to the accompanying drawings there is provided a window frame or casing 1 to which is detachably connected the improved rolling window screen generally designated by the number 2. ⁷⁵

In reducing the present invention to practice a pair of opposed guides 3 are employed and each guide is formed desirably from a single piece of sheet metal which is ⁸⁰ folded upon itself as at 4 providing spaced side portions 5 and 6 the inner of which is offset as at 7 while both of the side portions are bent inwardly toward each other and arranged in spaced parallel relation to provide ⁸⁵ bearing portions 8. Suitable fasteners such as screws 9 serve as a means for anchoring the guides in position on the opposite sides of the window casing and near the outer faces thereof as indicated. The upper terminals of the guides are shaped to provide trunnion receivers 10 in which are fitted the trunnions 11 of a spring roller 12. The body or screen 13 has one end secured to the roller 12 and is windable thereabout while ⁹⁰ also secured to the opposite sides of the body or screen 13 are steel tapes 14. Disk headed retainers 15 are now anchored to the tapes 14 adjacent their outer side edges and operate within the guides, the heads thereof bearing against the free inner edges of the bearing portions 8 of the guides so as to retain the tapes between the adjacent faces of the bearing portions, these parts cooperating ⁹⁵ in guiding the movement of the screen or body 13 when it is being pulled down or extended or when being wound up subsequent to release and in addition insure the maintenance of the body or screen in a substantially taut position when extended. ¹⁰⁰

In order to releasably hold the screen or body 13 in an extended position so as to

close the window casing a tube 16 is connected to the lower or free edge of the body or screen and is positioned transversely thereof. Catches 17 are telescopically arranged within the ends of the tube and are formed at the inner ends with handles 18 which operate through slots 19 near the ends of the tube while also positioned near the end of each tube is a coiled spring 20 the respective ends of which bear against the inner ends of the catch and against the partition 21 within the tube in such a manner as to exert tension on the catch to normally hold the catch extended and when extended the free outer portion thereof is arranged between the bearing surfaces or portions 8 of the guides 3 while the free terminal is designed to be arranged within the socket 22 of the adjacent keeper block 23 mounted in turn in the lower end of the adjacent guide 3 as indicated in the drawings. To release the catch it is only necessary to engage the handles and slide the catches toward the center of the tube against the tension of the springs to permit of the disengagement of the free ends of the catches from the sockets 22. In this connection it is to be observed particularly that the spring roller 12 is not provided with a catch which consequently assures of the spring of the roller 12 at all times exerting a tension on the screen so that subsequent to the release of the catches 17 the spring roller will act to automatically rewind both the body 13 and the tapes 14 about the roller.

A hood 24 is removably mounted over the roller and supported by the guides for preventing the action of the weather on the roller and screen when the latter is not in use.

The invention comprises means for laterally compressing the guides on the side edges of the screen when the latter is in extended position and for this purpose there is employed a pair of cam levers disposed on op-

posite sides of the window frame, each lever being pivotally mounted on a stud 26 carried by a bracket 27 mounted on the casing or frame by a fastener 28. Adjacent the peripheral edge of the cam and opposite the eye or aperture through which the stud 26 passes there is provided a laterally projecting flange 29 which, when the cams are disposed with the handles upwardly, as in Figure 1, are out of engagement with the bracket 27. The guides will then permit free movement of the screen. On rotating the cams, however, to dispose the handles downwardly, the flanges will engage behind the brackets 27 and force the cams into engagement with the adjacent facing of the guide and compress the guide to effect binding engagement on the interposed edges of the screen.

What is claimed is:

A device of the kind described comprising in combination with a spring actuated roller, a screen carried by the roller, resilient tapes secured to the side edges of the screen, guides for the side edges of the screen, each being formed from a single piece of sheet metal folded on itself to provide a flange for attachment to a vertical stile of a window frame, the guides being formed with spaced parallel side portions extending from the attaching flange, one of said side portions being offset from the flange but both being inturned at their free edges, the resilient tapes slidably engaging between the inturned portions of the guides, means carried by the screen at its edges and disposed within the guides to prevent lateral or sidewise movement of the screen, and means for moving the flanges of each guide towards each other to effect a clamping operation on the tapes and the adjacent edges of the screen for the purpose specified.

In testimony whereof I affix my signature.

ARTHUR YERLY.
